BURNER SUPPORT AND BURNER FOR
FURNACESDurbin Van Law, Denver, Colo., assignor to
Powderco, Inc., Denver, Colo.

Application January 23, 1934, Serial No. 707,909

6 Claims. (Cl. 110—28)

This invention relates to retorts for furnaces, its primary object being to provide apparatus for the introduction and ignition of powdered fuel, which as an entirety, can be placed in operative relation to a furnace of conventional construction, by insertion in the opening thereof normally closed by the fire door.

Another object resides in providing in association with apparatus of the above stated character, refractory means to concentrate and increase the heat in the combustion chamber of the furnace, whereby to obtain substantially complete combustion of the fuel stream at the maximum temperature.

15 A further object of the invention is to provide in apparatus of the above described character means to effect turbulence of a stream of secondary air drawn down into the furnace; and still other objects are to be found in details of construction and novel and advantageous arrangements and combinations of parts, all of which will be clearly brought out in the course of the following description.

In the accompanying drawing, in the several views of which like parts are similarly designated,

25 Figure 1 is an elevation of a furnace, in connection with a mill by which fuel-carrying air-currents are directed to a burner-unit which, in accordance with the present invention, is inserted in the fire-opening of the furnace,

30 Figure 2 is an enlarged vertical section of the furnace, inclusive of the burner-unit.

Figure 3 is a face view of the unit looking from within the furnace in the direction of the arrows 3.

35 Figure 4 is a section along the line 4—4 of Figure 2.

Figure 5 is a vertical section of the inner portion of the burner-unit, drawn to an enlarged 40 scale on the line 5—5 of Fig. 3, and

Figure 6 is a sectional view of the apertured plate of the unit by which secondary air is admitted to the furnace.

45 The furnace as shown at 4 is of the type commonly used for heating dwellings and other establishments of comparatively small size. The furnace has, as usual, an ash-opening 5, ordinarily closed by a door 6, and a fire-opening 7. The door which in the ordinary use of the furnace closes the fire-opening, is taken away for the application of the burner-unit in accordance with the present invention.

50 The unit, as best shown in Figure 5, comprises a flanged box 8 which fits into the fire-opening of the furnace; a flange 8a at the outer end of

the box engages the outer wall of the furnace, and the box may be fastened in place by a rim of cement applied over the flange as shown at 9 in Figure 2 of the drawing. It is to be understood, however, that other fastening means, such as bolts, may be employed to hold the box in place.

5 The inner wall 10 of the box extends in a plane slanting with relation to the body portion of the box and facing downwardly in an inclined plane when the box is in its operative position.

This inner end wall has a central opening 12, and around the same, smaller apertures 13 for the admission of secondary air. Extending into and through the central opening is the burner proper which consists of a block 14 of refractory material, having an axial passage 15 which at its outer end, connects with a conduit 16 through which fuel-carrying air-currents are supplied to the furnace from a mill 17, or other suitable source of supply.

20 Within the passage, preferably adjacent the end of the conduit 16, is a whirler 18 adapted to impart a whirling motion to the entering air-currents.

25 Embedded in the wall of the burner-block are two electrodes 19, the tips of which are spaced inside the flaring inner end portion of the passage to provide a spark-gap 20 by which in the operation, the fuel carried by the air-currents is 30 initially ignited. The electrodes are connected in circuit with a source of electric current as indicated at 21 in Figure 1.

35 Around the portion of the burner-block projecting through the central opening of the end plate 10 of the box 8 is a circumferentially flanged plate 22, spaced from the wall 10, to provide a narrow chamber 23 to receive the secondary air-currents drawn into the furnace through the apertures 13. The plate 22 has a 40 central opening through which the end of the burner-block projects, and it has around this opening a circular series of slanting vanes 24 formed by cutting U-shaped slits in the metal of which the plate is composed and bending the 45 strips within the slits outwardly as best shown in Figure 6.

45 The outer surface of the plate, around the series of vanes, is preferably covered with a 50 layer 25 of refractory clay or other similar material. The vanes 24 function as a whirler-element to impart a whirling motion to the secondary air-currents as they enter the combustion chamber of the furnace. It will be seen that owing to the slanting position of the end plate 10 55

of the box 8, the axis of the passage 15 in the burner-block 14 extends slantingly with relation to the vertical axis of the combustion chamber 26 of the furnace, so that the fuel-carrying air-currents enter the furnace through the passage of the burner-block in a downwardly inclined stream.

Opposite to the end plate of the box 8 is a baffle plate 27 of refractory material whose principal function is to reflect the heat into the coal stream.

The refractory coating 25 of the plate 22 has a similar effect.

In the operation of the furnace both the baffle 15 and the coating are heated, and the radiant heat being reflected into the fuel stream produces a high temperature with a correspondingly high degree of combustion. The whirling motion imparted to both the fuel-carrying air-currents 20 and the secondary air by the two whirler elements produces dissemination of the fuel inside the combustion chamber, which exposes each particle thereof to the heat after initial ignition as it passes the spark-gap 20.

25 The secondary air within the chamber 23, moreover, has a cooling effect to prevent the metal parts from being detrimentally affected by the heat of the furnace.

The downward direction of the fuel stream as 30 it enters the furnace gives to the fuel the benefit of the entire extent of the combustion chamber. The fuel in this manner is fed against a relatively still body of air in the lower portion of the chamber, causing the flames to spread across 35 the chamber. The result of this spreading effect and the reflective properties of the baffle and the coating of the plate 22 is the production and maintenance of a radiant heat of high temperature resulting in rapid and substantially complete combustion.

40 It is a distinctive feature of the invention that the unit, mounted and assembled as an entirety, is readily slipped into the fire-opening after the door thereof has been removed, and is then fastened in place. The application of the device 45 therefore requires no alteration in the construction of the furnace whatsoever, with the possible exception of the provision of the slanting baffle plate 27, which, as shown in the drawing, extends to the floor of the furnace and terminates at a distance from the ash-opening so as not to interfere with the removal of the ashes.

It is to be understood that in using the term 55 "furnace" in the foregoing description and the hereunto appended claims are included not only heating devices, such as are used in residences and other similar establishments, but also small boilers and other devices used for other than heating purposes.

60 What I claim and desire to secure by Letters Patent is:

1. The combination with a furnace having a combustion chamber and a fire-opening for the supply of fuel to the chamber, of a burner-unit 65 comprising a box in the fire-opening, open at its outer end and having an inner end wall slantingly facing downwardly and located in the combustion chamber, the inner end wall having an aperture for a burner-block and an aperture 70 for the admission of secondary air to the combustion chamber, a burner-block in the first-mentioned aperture having a passage substantially perpendicular to the end wall for the entry of downwardly directed fuel-carrying air-currents into the combustion chamber, and a re-

fractory plate located in the combustion chamber in the path of the fuel stream.

2. The combination with a furnace having a combustion chamber and a fire-opening for the supply of fuel to the chamber, of a burner-unit 5 comprising a box in the fire-opening, open at its outer end and having an inner end wall slantingly facing downwardly and located in the combustion chamber, the end wall having an aperture for a burner-block and an aperture for the admission of secondary air to the combustion chamber, a burner-block in the first-mentioned aperture having a passage substantially perpendicular to the end wall for the entry of downwardly directed fuel-carrying air-currents into 15 the combustion chamber, and a plate spaced from the end wall to provide a chamber to receive the secondary air, said plate having an opening through which the burner block extends, and openings surrounding the burner block. 20

3. The combination with a furnace having a combustion chamber and a fire-opening for the supply of fuel to the chamber, of a burner-unit 25 comprising a box in the fire-opening, open at its outer end and having an inner end wall slantingly facing downwardly and located in the combustion chamber, the inner end wall having an aperture for a burner-block and an aperture for the admission of secondary air to the combustion chamber, a burner-block in the first-mentioned 30 aperture having a passage for the entry of downwardly directed fuel-carrying air-currents into the combustion chamber, and a plate spaced from the end wall to provide a chamber to receive the secondary air, said plate having an opening through which the burner block projects and openings having slanting vanes for causing turbulence of the secondary air upon its entering 35 the combustion chamber.

4. The combination with a furnace having a 40 combustion chamber and a fire-opening for the supply of fuel to the chamber, of a burner-unit comprising a box in the fire-opening, open at its outer end and having an inner end wall slantingly facing downwardly and located in the combustion chamber, the inner end wall having an aperture for a burner-block and an aperture 45 for the admission of secondary air to the combustion chamber, a burner-block in the first-mentioned aperture having a passage for the entry of downwardly directed fuel-carrying air-currents into the combustion chamber, a plate spaced from the end wall to provide a chamber to receive the secondary air, said plate having an opening through which the burner block projects and a 50 coating of refractory material upon the outer surface of the plate.

5. The combination with a furnace having a combustion chamber and a fire-opening for the supply of fuel to the chamber, of a burner-unit 60 comprising a box in the fire-opening, open at its outer end and having an inner end wall slantingly facing downwardly and located in the combustion chamber, the inner end wall having an aperture for a burner-block and an aperture 65 for the admission of secondary air to the combustion chamber, a burner-block in the first-mentioned aperture having a passage for the entry of downwardly directed fuel-carrying air-currents into the combustion chamber, a plate spaced from the 70 end wall to provide a chamber to receive the secondary air, said plate having an opening thru which the burner block projects, a coating of refractory material upon the outer surface of the plate, and a baffle of refractory material opposed 75

to said coating and in the path of the fuel stream.

6. A burner unit for use with a furnace having a fire-opening, comprising a box-like member, for insertion into the opening, open at its outer end and having an inner wall which slantingly faces downwardly when it is in position, the inner wall being provided with an opening, a fuel nozzle

comprising a burner-block projecting thru the opening, the inner wall being also provided with an opening for the admission of auxiliary air, and means located on the outer side of the inner wall for imparting a whirling motion to the auxiliary air. 5
